[57] CLAIM

The ornamental design for a lens cleaning device, as shown and described.

DESCRIPTION

FIG. 1 is a perspective view of a lens cleaning device in accordance with my design.

FIG. 2 is a front elevational view thereof;

FIG. 3 is a back view thereof;

FIG. 4 is a cap end elevational view thereof;

FIG. 5 is a clip end elevational view thereof;

FIG. 6 is a top plan view thereof;

FIG. 7 is a bottom plan view thereof;

FIG. 8 is a top plan view thereof, with a cap segment of the lens cleaning device moved to expose a cleaning pad of a cleaning pad segment of the lens cleaning device, the cap segment placed for storage on the clip end of the lens cleaning device;

FIG. 9 is a top plan view of the lens cleaning device of FIG. 1, with the cap and cleaning pad segments moved to expose a brush segment of the lens cleaning device, a brush if the brush shown in an extended position, the cleaning pad segment and cap segments, respectively, placed for storage on the clip end of the lens cleaning device;

FIG. 10 is a top plan view of the lens cleaning device of FIG. 1, with the cap and cleaning pad segments moved to expose the brush segment of the lens cleaning device, the brush of the brush segment shown in the extended position, the cap segment placed for storage on the clip end of the lens cleaning device, the cleaning pad segment placed on the cap segment so that the cleaning pad of the cleaning pad segment is exposed;

FIG. 11 is a top plan view of the lens cleaning device of FIG. 9, with the brush shown in a retracted position; and, FIG. 12 is a top plan view of the lens cleaning device of FIG. 10, with the brush shown in the retracted position.

The broken lines showing of surface indicia in FIGS. 1 and 2 are illustrative of environmental features only and constitute no part of the claimed design.
